UNITED STATES PATENT OFFICE.

GUSTAVE L. HERZ, OF NEW YORK, N. Y.

SPARK-PLUG.

1,306,304.

Specification of Letters Patent. Patented June 10, 1919.

Application filed October 25, 1915. Serial No. 57,805.

To all whom it may concern:

Be it known that I, GUSTAVE L. HERZ, a citizen of the United States, and resident of the borough of Manhattan, in the city 5 and State of New York, have invented a new and useful Improvement in Spark-Plugs, of which the following is a specification.

The object of my invention is to provide certain improvements in the construction, 10 form and arrangement of the several parts of a spark plug whereby, first, the liability of the sparking electrodes becoming clogged with oil is eliminated; second, the protection of the outwardly projecting portion of 15 the insulating block is insured, and third, the protection of the electrical connection between the conducting cable and the spark plug is insured.

A practical embodiment of my invention 20 is represented in the accompanying drawings, in which,

Figure 1 is an outer end view of the plug.

Fig. 2 is a side view of the plug.

Fig. 3 is a longitudinal central section 25 through the plug, and

Fig. 4 is an inner end view of the plug.

The insulator has an enlarged middle portion 1 and reduced ends 2, 3, forming exterior shoulders 4, 5. The hollow shell 6 is 30 provided with interior shoulders 7, 8, between which and the shoulders 4, 5, are interposed gaskets 9, 10, for spacing the insulator from the inner walls of the shell.

The inner end of the shell 6 forms one of 35 the sparking electrodes. In the present instance this inner end comprises a skeleton disk 11 clamped to the shell, provided with spirally arranged arms 12 presenting their ends flatwise to the opposite sides of the inner end of the conductor 13 which extends 40 axially through the insulator and forms the other sparking electrode. A nut 14 engages the screw-threaded outer end of the conductor 13 and serves, together with the shoulder 15 on the said conductor and the insulating core 16, against the inner end 45 of which the shoulder bears, to secure the conductor to the block.

A hood 17 of insulating material 50 rounds the nut 14 and the outwardly projecting end 3 of the insulator, the inner end of which hood is provided with a copper or other soft metal rim 18, bearing against the outer end of the shell 6. The outer end of 55 the hood has a recess 19, the bottom of which is substantially flush with the outer

face of the nut 14. An exterior annular seat 20 is provided at the outer end of the hood for receiving the annular flange 21 of the non-conducting outer portion 22 of a cap, 60 the metallic conducting inner portion 23 of which slides freely along the screw-threaded portion of the conductor 13 and extends inwardly beyond the inner face of the non-conducting portion 22, into the recess 19 65 and forms together with the flange 21, a recess for receiving the annular flange 24 at the outer end of the said hood 17.

A thumb nut comprising a metallic inner 70 conducting portion 25 and an outer non-conducting portion 26, has a screw-threaded engagement with the outer end of the conductor 13, and bears against the metallic conducting inner portion of the cap for forcing the cap into snug engagement with 75 the outer end of the hood 17.

The electric conducting cable comprises the usual core 27 and protective covering 28. The eye portion of a screw eye terminal 29, is inserted into the recess 19 between the 80 adjacent faces of the nut 14 and metallic inner conducting portion 23 of the cap, which eye surrounds the conductor 13. The screw-threaded portion of the screw eye is engaged with the core 27 of the electric conducting cable and the covering 28 of the said cable is inserted between the hood 17 and the cap by cutting away the side walls of the hood and cap, as indicated at 80, 81. If so desired, the non-conducting outer portion 22 of the cap may be reinforced as 85 shown at 82, at the cutaway portion 31, to prevent any danger of the cap becoming broken at this point when pressure is applied thereto by the thumb nut. 90

From the above description it will be seen that by providing spirally arranged arms for the sparking electrode of the shell, the accumulation of oil on the said arms is prevented. 95

It will furthermore be seen that the provision of the hood materially strengthens the exposed end of the spark plug and that the connecting end of the conducting cable is very completely and effectually housed, 100 not only the screw eye terminal being protected but also the end of the covering of the cable.

It will furthermore be seen that the cable may be led in any direction from the spark 110 plug by loosening the thumb nut sufficiently to permit the rotative movement of the hood.

and its cap, the cable being clamped in any desired relative position by simply tightening the thumb nut to the desired extent.

Any liability of the hood becoming broken is obviated by the copper or other soft metal rim at its inner end and the engagement of the non-conducting outer portion of the cap with its outer end. At the same time it will be seen that the pressure applied by the screwing up of the thumb nut will be chiefly against the metallic conducting elements, thus relieving the non-metallic or non-conducting elements from this strain.

It is evident that various changes may be resorted to in the form, construction and arrangement of the several parts without departing from the spirit and scope of my invention, and hence I do not wish to limit myself strictly to the structure herein set forth, but

What I claim is:

1. In a spark plug, the shell, insulator and conductor, the inner end of the shell having spirally arranged arms presenting their ends to the inner end of the conductor.
2. In a spark plug, the shell, insulator and conductor, the inner end of the shell having flat spirally arranged arms twisted to present their ends to the inner end of the conductor.
3. In a spark plug, the shell, insulator and conductor and a skeleton disk at the inner end of the shell having spirally arranged arms presenting their ends to the inner end of the conductor.
4. In a spark plug, the shell, insulator and conductor and a skeleton disk at the inner end of the shell having flat spirally arranged arms twisted to present their ends to the inner end of the conductor.
5. In a spark plug, the shell, insulator and conductor, the inner end of the shell being provided with flat spirally arranged arms twisted to present their ends flatwise to the inner end of the conductor.
6. In a spark plug, the shell, insulator and conductor and a skeleton disk at the inner end of the shell provided with flat spirally arranged arms twisted to present their ends flatwise to the inner end of the conductor.
7. In a spark plug, the shell, insulator and conductor, a non-conducting hood and a non-conducting cap arranged to receive between them the terminal of a conducting cable, and means for clamping the hood, terminal and cap in position.
8. In a spark plug, the shell, insulator and conductor, a non-conducting hood and a non-conducting cap shaped to snugly em-

brace the terminal of a conducting cable, and means for clamping the hood, terminal and cap in position.

9. In a spark plug, the shell, insulator and conductor, a non-conducting hood having a recess in its outer end for receiving the terminal of a conducting cable, a non-conducting cap for closing said recess and means for clamping the hood, terminal and cap in position.

10. In a spark plug, the shell, insulator and conductor, a non-conducting hood having a recess in its outer end for receiving the terminal of a conducting cable, a non-conducting cap for closing said recess and means for clamping the hood, terminal and cap in position, said cap and hood being shaped to snugly embrace the protective covering of said cable.

11. In a spark plug, the shell, insulator, conductor and its securing nut, a non-conducting hood and a non-conducting cap for receiving between them the terminal of a conducting cable, and means for clamping the hood, terminal and cap in position, said cap having a metallic conducting inner portion for pressing the terminal against said nut.

12. In a spark plug, the shell, insulator, conductor and its securing nut, a non-conducting hood and a cap for receiving between them the terminal of a conducting cable, a thumb nut for clamping the hood, terminal and cap in position, said cap and thumb nut both having non-conducting outer portions and metallic inner portions.

13. In a spark plug, the shell, insulator and conductor, a non-conducting hood and a non-conducting cap arranged to receive between them the terminal and protective covering of a conducting cable and means for clamping the hood, cable and cap together.

14. In a spark plug, the shell, insulator and conductor, a non-conducting hood, a cap having a conducting inner portion and a non-conducting outer portion, a nut engaging the conductor and located within the hood, the hood and the non-conducting portion of the cap being arranged to receive the protective covering of a conducting cable and the said nut and conducting portion of the cap being arranged to receive the terminal of said conducting cable, and means for clamping the hood, cable and cap together.

In testimony, that I claim the foregoing as my invention, I have signed my name this 23rd day of October, 1915,

GUSTAVE L. HERZ.
